UNITED STATES PATENT OFFICE.

WILLIAM B. STEARNS, OF MARBLEHEAD, MASSACHUSETTS.

SKYLIGHT FOR VESSELS.

SPECIFICATION forming part of Letters Patent No. 731,138, dated June 16, 1903.

Application filed February 24, 1903. Serial No. 144,571. (No model.)

To all whom it may concern:

Be it known that I, WILLIAM B. STEARNS, of Marblehead, county of Essex, and State of Massachusetts, have invented an Improvement in Skylights for Vessels, of which the following description, in connection with the accompanying drawings, is a specification, like characters on the drawings representing like parts.

10 This invention relates to skylights especially adapted for yachts and vessels, although not limited to this particular use, and has for its object to construct a skylight with a water-tight hinge connection devoid of packing, 15 the parts of which preferably interlock in such manner as to prevent the skylight being removed unless it is opened wide, or nearly so.

Figure 1 shows in perspective a skylight embodying this invention. Fig. 2 shows a 20 transverse section of the hinge connection of the skylight with the ridge, taken on an enlarged scale, on line 2 2 of Fig. 1. Fig. 3 is a detail of the plate at the end of the ridge, having holes through it which serve as exits 25 for the gutters on the ridge.

For the purpose of illustrating a practical embodiment of my invention as applied to yachts and vessels I have herein shown two 30 skylights hinged to a single ridge; but it is obvious that a single skylight hinged to a ridge in a similar manner comes within the scope of my invention.

The skylight *a* comprises a sash or frame of any suitable size and shape, having one or 35 more lights of glass *a'* set into it in any usual or suitable manner. Along the upper edge of the sash or frame the leaf or plate *b* of the hinge is secured, which extends the entire length of the skylight, or nearly so, and, as 40 herein shown, said leaf has projecting downwardly from it at right angles an integrally-formed lip *b'*, which is adapted to be secured to the upper edge of the sash or frame. For small sashes or frames either the leaf *b* or the 45 projecting lip *b'* may be omitted, the part remaining serving as the leaf. The leaf of the hinge has an extension *b*², preferably formed integral therewith, which is formed with a semicircular portion *b*³, hollowed on its under 50 side and having at its outer edge a projecting lip or shoulder *b*⁴. I prefer to make the portion *b*³ semicircular, although I do not desire

to limit my invention to this particular shape; yet to operate effectively it should have a semicircular recess at its under side to receive a circularly-formed pivot on the ridge or stationary member of the hinge, to be described.

The ridge comprises, essentially, a base or body portion *c*, adapted to be placed upon and secured to a pole, strip, or bar *d*, and at one or both sides thereof a curved extension *c'*, which is of suitable size and shape to serve as and constitute a gutter.

The circularly-formed pivot *c*², which enters the recess or hollow in the semicircular portion *b*³, is located at the outer edge of the gutter and is preferably formed integral with the ridge. The highest point of the pivot *c*² is preferably higher than the base or body portion *c*, so that in case the gutter should fill with water or snow by any chance no water would flow into the boat. If desired, a row of rolls or balls *i* may be placed in a groove formed in the top of the circular bearing *c*².

A lip or shoulder *c*³ projects from the base *c* toward the circularly-formed pivot *c*² and partially closes the opening or space which serves as the entrance to the gutter. One or both ends of the gutter are provided with plates *n*, having holes *n'* through them. The hollow semicircular portion *b*³ on the movable member of the hinge connection is made of a thickness nearly equal to the width of the opening or entrance to the gutter and projects through said opening or entrance to the gutter, so as to substantially close said opening or entrance at all times regardless of the position of the skylight, and the lip or shoulder *b*⁴, which is located at the outer edge of said semicircular portion *b*³, occupies a position below the lip or shoulder *c*³ on the ridge, and when the skylight is closed said lip or shoulder *b*⁴ either abuts against the lip or shoulder *c*³ or is brought close up to it. The hinge thus constructed in some respects resembles and works like a ball-and-socket joint, the semicircular portion *b*³ resting upon and working on the circularly-formed pivot *c*² as the skylight is operated. The hollow or recessed semicircular portion which projects through the opening or entrance and down into the gutter works in said opening or entrance as the skylight is operated, and the entrance to

said gutter is practically closed at all times; yet any water which passes into the gutter will make its escape through the exits at the ends thereof. Furthermore, by providing the 5 semicircular portion b^3 with the lip or shoulder b^4 and providing the ridge with the lip or shoulder c^3 the parts will interlock in such manner that the skylight cannot be removed except when opened wide, or nearly so. It 10 is obvious that the extent of this interlocking may be varied, for example, by varying the size of the opening between c^2 and c^3 with reference to the size of the lip b^4 .

Having thus described my invention, what 15 I claim as new, and desire to secure by Letters Patent, is—

1. In a skylight, the combination of a ridge having a gutter, a skylight hinged to the outer edge of said gutter having means for substantially closing the entrance to said gutter, substantially as described.

2. In a skylight, the combination of a ridge having a gutter provided with a pivot on which the skylight works, and a skylight having a 25 hinged member which interiorly engages said pivot, and means connected with said hinged member which projects into and substantially closes the entrance to said gutter and works in said entrance as the skylight is operated, 30 substantially as described.

3. In a skylight, the combination of a ridge having a gutter provided with a circularly-formed pivot at its outer edge and a skylight having a leaf secured to it provided with an 35 extension having a hollow semicircular portion which interiorly engages the pivot on the gutter, substantially as described.

4. In a skylight, the combination of a ridge having a gutter provided with a circularly-formed pivot and a skylight having a leaf secured to it provided with an extension having a semicircular portion which engages said pivot and which projects into the gutter and substantially closes the entrance thereto, sub- 45 stantially as described.

5. In a skylight, the combination of a ridge

having a gutter and also having an interlocking member, and a skylight hinged to said ridge having an interlocking member which crosses the entrance to the gutter and coöperates with the interlocking member on the ridge, substantially as described. 50

6. In a skylight, the combination of a ridge having a gutter and a projecting lip or shoulder, and a skylight hinged thereto having a 55 lip or shoulder which works in said gutter and which projects beneath the lip or shoulder on the ridge to thereby interlock the parts, substantially as described.

7. In a skylight, the combination of a ridge 60 having a gutter, a circularly-formed pivot and a projecting lip or shoulder and a skylight having a leaf with an extension thereon having a hollow semicircular portion which interiorly engages said pivot and having a projecting lip or shoulder which works in said gutter and engages the lip or shoulder on the ridge, substantially as described. 65

8. In a skylight, the combination of a ridge having a gutter and a lip or shoulder which 70 partially closes the entrance thereto, a skylight, a hinge member thereon which engages the edge of said gutter, having an extension which projects through the entrance to said gutter and also having a lip or shoulder which 75 coöperates with the lip or shoulder on the ridge, substantially as described.

9. In a skylight, the combination of a ridge comprising a base and a gutter at one side thereof a circularly-formed pivot at the outer 80 edge of the gutter which projects above the level of the base of the ridge, and a skylight having a hinged member which interiorly engages said pivot, substantially as described.

In testimony whereof I have signed my 85 name to this specification in the presence of two subscribing witnesses.

WILLIAM B. STEARNS.
